US00D983761S

(12) **United States Design Patent** (10) **Patent No.:** **US D983,761 S**
(45) **Date of Patent:** **** Apr. 18, 2023**

(54) **TELEVISION APPARATUS**

(71) Applicant: **LG ELECTRONICS INC.**, Seoul (KR)

(72) Inventors: **Jaewon Lim**, Seoul (KR); **Yongho Lee**, Seoul (KR); **Sechang Park**, Seoul (KR)

(73) Assignee: **LG ELECTRONICS INC.**, Seoul (KR)

(**) Term: **15 Years**

(21) Appl. No.: **35/513,437**

(22) Filed: **Jul. 26, 2021**

(80) **Hague Agreement Data**

Int. Filing Date: **Jul. 26, 2021**

Int. Reg. No.: **DM/216194**

Int. Reg. Date: **Jul. 26, 2021**

Int. Reg. Pub. Date: **Jan. 28, 2022**

(30) **Foreign Application Priority Data**

Feb. 22, 2021 (KR) 30-2021-0008799

(51) **LOC (14) Cl.** **14-03**

(57) **CLAIM**

The ornamental design for a television apparatus, as shown and described.

DESCRIPTION

1. Television apparatus

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

1.15 : Perspective

1.16 : Front

1.17 : Back

1.18 : Left

1.19 : Right

1.20 : Top

1.21 : Bottom

The broken lines indicate portions of the article that form no part of the claimed design; reproductions 1.1 to 1.7 show the claimed design in a first position; reproductions 1.8 to 1.14 show the claimed design with its screen partially sliding up; and reproductions 1.15 to 1.21 show the claimed design with its screen fully sliding up.

1 Claim, 21 Drawing Sheets
